DESIGN FOR A CULINARY CUTTING BLADE

John A. Waller, Beverly Hills, Calif.

Application July 14, 1939, Serial No. 86,006

Term of patent 14 years

To all whom it may concern:

Be it known that I, John A. Waller, a citizen of the United States, residing at Beverly Hills, in the county of Los Angeles, State of California, have invented a new, original, and ornamental Design for a Culinary Cutting Blade, of which the following is a specification, reference being had to the accompanying drawing, forming a part thereof.

Fig. 1 is a top plan view of the culinary cutting blade, showing my new design;

Fig. 2 is an inverted plan view thereof; Fig. 3 is an end elevation thereof; and Fig. 4 is a transverse section thereof taken on line 4—4 of Fig. 1, showing the configuration of the device adjacent the mid-length thereof.

I claim:

The ornamental design for a culinary cutting blade, as shown.

JOHN A. WALLER.
